(57) **CLAIM**

The ornamental design for a bag, as shown and described.

DESCRIPTION

FIG. 1 is a perspective view of the bag showing my new design;

FIG. 2 is a perspective view thereof with a top overlapping flap cover in an open state;

FIG. 3 is a perspective view thereof with a zippered cover in an open state;

FIG. 4 is a front view thereof;

FIG. 5 is rear view thereof;

FIG. 6 is a right side view thereof;

FIG. 7 is a left side view thereof;

FIG. 8 is a top view thereof with the top overlapping flap cover in a closed state;

FIG. 9 is a top view thereof with the top overlapping flap cover in an open state; and,

FIG. 10 is a bottom view thereof.

The broken lines depict portions of the bag that form no part of the claimed design.

1 Claim, 9 Drawing Sheets
